UNITED STATES PATENT OFFICE.

RICHARD H. CUNNINGHAM, OF NEW YORK, N. Y.

IGNITION APPARATUS FOR AUTOMOBILES AND THE LIKE.

1,127,197.

Specification of Letters Patent.

Patented Feb. 2, 1915.

Application filed July 13, 1912. Serial No. 709,215.

To all whom it may concern:

Be it known that I, RICHARD H. CUNNINGHAM, a citizen of the United States, residing at the city of New York, in the 5 borough of Manhattan and State of New York, have invented certain new and useful Improvements in Ignition Apparatus for Automobiles and the like, of which the following is a full, clear, and exact description.

This invention relates to ignition apparatus for internal combustion engines such as are used on automobiles, and the like, and more particularly to a combined switch, induction coil and container adapted to be mounted upon and concealed in the dashboard of such vehicles.

It has for one of its objects the simplification of devices of this character whereby the 20 several elements thereof are rendered more accessible and also whereby in the event of any part becoming impaired, as for example if the induction coil insulation becomes electrically perforated or broken down, the 25 windings thereof can be readily removed and replaced with others, if desired, without necessitating the waste of other and adjacent elements or material.

I have further aimed to improve the magnetic field of the coil and to facilitate air 30 cooling of the iron parts of said coil.

The preferred construction embodies novel switch parts which are particularly well adapted to the principal ends sought,— 35 namely, simplicity and compactness of the device as a whole, and the provision of a substantial and waterproof construction adapted to withstand rough usage, vibration and moisture.

40 These and other objects of the invention will be hereinafter referred to and the novel elements and combination of elements whereby they are attained will be more particularly set forth in the claims appended 45 hereto.

In the drawings which form a part hereof and in which like reference characters designate like parts throughout the several views, I have exemplified a preferred construction, 50 but I am aware that various changes may be made therein without departing from the spirit of the invention and hence desire to be limited only by the scope of said claims.

Referring to the drawings: Figure 1 is 55 a vertical median section of a combined switch, coil and container. Fig. 2 is an elevation of the switch end of the same. Fig. 3 is a detail of the switch showing the disposition of the spring contacts therein; the 60 switch cap being removed. Fig. 3^a is a fragmentary detail section of an insulating disk upon which said contacts are mounted; the section being taken on line III—III of Fig. 3. Fig. 4 is an elevation of the inner 65 side of the switch cap. Fig. 5 is an elevation of the opposite end of the structure, the protective insulating covers being removed. Fig. 6 is a somewhat diagrammatic perspective view of the device showing the 70 electrical connections between the switch, induction coil, condensers and binding posts. Fig. 7 is a side elevation of the device, drawn to a smaller scale, and with the switch-cap removed. Fig. 8 is a transverse 75 section taken on line VIII—VIII of Fig. 1.

The preferred construction comprises a flanged switch-cap 1 of metal or other suitable material, the flange thereof being perforated, as at 2, for the reception of screws 3 80 whereby it may be secured to a base 4. Additional holes 2' are also provided for screws 3' of sufficient length to extend through both the flange and base into the dashboard to which the base is thereby secured. 85

The cap 1 is hollow and its outer side is apertured at 5, but this aperture is closed by a disk 6 which is pressed, not too tightly, outward against an inwardly projecting 90 flange 7. The disk 6 carries upon one side thereof an operating handle 8 and on the other an insulating selector disk 9 of fiber, or the like, these three parts being secured together by screws 10, or the like. The handle is massive so that it may be struck by the foot of the operator, if desired, without possibility of injury thereto, and as it is rotated it carries around the fiber disk 9 in which are inserted arcuate contact strips 11 100 and 12; the latter being flush with the inner side of the fiber disk, as indicated in Fig. 1.

The edge of the disk 9 is notched at 13 for the reception of the extremity of a locking bolt 14 mounted in an extension 15 of 105 the cap 1. This extension for convenience of manufacture may be made separate from the cap, proper, and may be secured there-

to in any suitable fashion. It consists preferably of two blocks 16 and 17, screwed together; the former being solid and the latter bored for the reception of a spindle 18, 5 having an eccentric portion 19 positioned to bear against the head of the bolt 14. The latter is normally pressed outwardly by a spring 20 into engagement with the eccentric so that as the latter is rotated the bolt 10 is drawn inwardly or spring pressed outwardly, as the case may be. The boss 21 of the block 17 is slotted for the reception of a key, as is also the hollow, reduced extremity of the spindle which projects thereinto, so that when the proper key is inserted the eccentric may be rotated and the disk 9 thereby locked against rotation by its handle, or 15 unlocked, as desired. Disk 9 is also notched at 22, 23 and 24 to adapt it for co-action with a spring detent 25, whereby the rotary element of the switch may be held against inadvertent displacement in either of these positions.

To relieve the detent from undue strain, 25 the handle 8 is adapted for engagement at the respective ends of its travel, with the heads of the screws 2 respectively disposed on either side thereof, said screws hence serving as stops. The handle is recessed as 30 at 26 and a spring 27 therein normally pushes outwardly what is in effect, a push button 28. The inner end of the push button carries an insulating piece 29 which is held in place by a screw 30. The base has 35 mounted thereon an insulating block or disk 31, secured thereto, in any suitable manner, as by screws 32. The outer side of disk 31 is centrally recessed at 33 and radial recesses 34 extending outwardly from 40 this central aperture receive the somewhat C-shaped leaves of the spring contacts. These contacts preferably consist of a series of bent bronze leaves, as shown in Fig. 3^a, the outermost leaf carrying a copper contact button 35; the leaves being held in place 45 in their recesses 34 by bolts hereinafter referred to, which serve as binding posts when needed.

Within the cavity 33 is an L-shaped, substantially flat, contact spring 36, one end of which is secured beneath one of the leaved contacts, designated 37, while the other extremity thereof, carries a contact button 38 normally held in engagement with a contact button 39, the latter being carried by the outer wing of a C-shaped contact bracket 40, as shown in Figs. 1 and 3. Substantially at the elbow of the member 36 is a similar depending button 41, which is normally held out of contact with a button 42 mounted on the exposed side of a conductive strip 43 which extends from the center of the cavity 33 to and into contact with the bracket 40 as indicated in Figs. 1 and 3. 65 Thus when the switch cap is in place upon

the base, and the push button is depressed, it momentarily breaks the circuit which includes the spring 36 and bracket 40, but immediately closes the circuit by the engagement of the contact buttons 41-42. The release of the push button effects a similar breaking and making of the circuit.

The base 4 is flanged at 45 and provided with a groove 46, and a cylindrical casing 47 is adapted to receive this flange into one end thereof, the edge of the casing being beveled to fit the correspondingly shaped groove 46. The casing may be of fiber or other suitable insulating material and is held in place upon the base 4 by means of two long bolts 48-49. The heads of these bolts bear against inwardly directed flanges or ears 50 of the base 4 and are disposed in a cavity 51 in the inner side of the disk 31. Said bolts are both threaded for substantially their entire length; bolt 48 being but little longer than the casing and bolt 49 being materially longer for reasons hereinafter given. The opposite extremity of the casing 47 is engaged by a ring 52 which has a flange 53 and groove 54 similar to those of the base 4, previously described. Ring 52 is urged into close engagement with the casing by a circular block 55, preferably of insulating material, 95 which is flanged as at 56 to adapt it to bear against the ring. The bolts 48-49 extend through this block; the short bolt 48 having a nut 57 at its outer extremity which clamps the block, ring, casing and base together, on 100 one side thereof. Secured within the block 55, opposite bolt 48, is a brass bushing 58 through which extends the bolt 49, and a nut 57' corresponding to nut 57 is threaded onto bolt 49 and bears against this bushing, whereby to clamp the other side of the assembled block, ring, casing and base together.

An insulating cover 59, having recesses 60 in its inner side for the reception of nuts 110 57-57', overlies the block 55 and is held in place thereon by a nut 61 threaded onto the bolt 49. Over this cover is an outer cover or protective cap 62, also of insulating material, through which extends the extremity 115 of bolt 49, a nut 63 being screwed down thereupon and holding said cap in place, so that even were the nut 61 to be omitted, the inner cover 59 would still be retained against displacement by the outer cover or 120 cap, the flange 64 of the latter engaging the rabbetted edge 65 of the inner cover. This flange 64 is cut away for a short distance, as at 66, to permit of the egress of the high tension lead and other connections underneath. The block 55 is centrally apertured for the reception of a brass stud 67 having a small bore 68 extending therethrough. A portion of the shank of this stud is threaded 125 for engagement with a hexagonal nut 69 and 130

a cap like nut 70. Block 55 is also provided with a recess 71 which extends from the center of the block outwardly to and around the bolt 49. A strip of mica 72 of the same shape as this recess is seated in the bottom thereof, said strip being perforated for the reception of the bolt 49 and the unthreaded portion of the shank of the stud 67. Against this mica strip and upon said shank 10 is a brass washer 73 abutting against which is a perforated blank or plate 74 of conductive material, cut, as shown in Fig. 5, so that a blunt point thereof extends toward the bolt 49. In contact with the blank 74 15 is a second brass washer 75, and outside of this latter is a second strip of mica 76, similar to the first; while a third washer 77 is pressed against the mica strip 76 by the nut 69 and thereby clamps the inner washers 20 and mica strips together. Similarly the nut 58 on bolt 49 has a reduced portion upon which are disposed the other extremities of the mica strips and a second pointed blank or plate 77, the strips and plate being spaced 25 apart by washers in the same manner as above described, and being clamped together by the nut 57'. The spaced pointed plates 74-77 constitute safety-gap electrodes between which a high tension discharge may 30 take place in the event of an excess voltage being generated from any cause; and the mica strips serve to inclose this spark or discharge.

Within the cavity formed by flange 45 of 35 the base and upon the bolts 48-49 are nuts 78 which support a pressure plate 79 against which is pressed a condenser 80 consisting of condenser plates 81 separated by layers 82 of mica or the like; the plates being wrapped 40 in a suitable insulating and waterproof covering 83. A second and similar condenser 84 is pressed against the first by a second pressure plate 85 slidably mounted on bolts 48-49 and held in place by nuts 86 45 on the respective tie bolts 48-49. These condensers *per se* form no part of the present invention and may be of any well known construction; the essential point to be considered in connection therewith being the 50 fact that the plates thereof are at all times pressed as closely together as practically possible, owing to the manner in which they are mounted in the device.

An induction coil comprising a primary winding 87 and secondary winding 88 is 55 also positioned in the container or casing 47, the magnetic core 89 thereof consisting of laminæ of soft iron, each iron sheet being substantially T-shaped, as shown in Fig. 8; the stems of the T's extending alternately in opposite directions. Each lamina is perforated so that it may be strung upon the tie bolts 48-49 and the entire coil is readily 60 assembled by inserting the stems of the T's 65 through the aperture in the windings, alin-

ing the bolt hole apertures and inserting the tie bolts (which had previously been secured to the base by nuts 78 and had had the condensers and pressure plates in turn secured thereupon) through said apertures until the 70 lowermost lamina bears against the supporting nuts 90, provided therefor. A wrapping 91 may also, if desired, be disposed around the assembled core; said wrapping consisting of a strip of soft iron of the width of 75 the assembled laminæ, when compressed, and being provided with supporting ears 92 perforated to receive the tie-bolts. Sleeves 93 are then pushed down over the bolts 48-49, the block 55 is applied, and the remaining parts in their obvious order. Nuts 57-57' when screwed down compress the laminæ together through the instrumentality of sleeves 93, while the so-assembled core in turn supports its windings. Thus the assembly or dis-assembly of the various parts is made exceedingly easy and one unskilled in the use of tools can remove a winding which has been electrically perforated or has otherwise become short-circuited, by the 85 use merely of a wrench.

The construction of the laminated core in the manner described not only aids assembly and dis-assembly of the device, but gives a very uniform magnetic field and 90 greatly facilitates heat radiation owing to the open air spaces around the heads of the T-shaped laminæ. In this connection it may be noted that it is desirable to perforate or even to quite widely aperture the 100 walls of the tubular container or casing 47, as indicated at 94, to permit of a free circulation of air about the magnetic core whereby to maintain the latter quite cool when 105 in use.

The suitably insulated primary and secondary windings may, of course, be formed by winding the wires thereof on a form.

The pressure plates 79 and 85 together constitute, in effect, a condenser retainer, 110 and the advantage of holding the condenser plates or foils under pressure thereby is obvious in view of the tendency for the components of a condenser, when hot, as they become in use, to spread apart and open up, 115 thereby decreasing the condenser capacity.

Electrical connections.—Referring to Figs. 2, 3 and 6, and assuming first that current is supplied to the apparatus from the armature of a magneto 95, the switch handle in 120 Fig. 2 being turned to the left into the position marked M. Current flows from the armature via a lead 96 to post 97, thence over wire 98 to post or bolt 99', which is one of the bolts referred to in connection with the general description of the C-shaped spring contacts in the switch. The corresponding bolt to any given one of these contacts has for convenience been designated with the same numeral as is used to indi- 125 130

cate the contact, but the bolt designating number has in each case been primed. Thus the contact carried by bolt 99' is marked 99, and since this contact is in engagement with the contact segment 12 of the selector disk 9, owing to the position of the switch, current flows to contact 100, which is also in engagement with said segment. Thence it passes to the corresponding bolt 100', where it branches, a portion traversing wire 101 to the binding post 102' and from thence back to an insulated bracket 102 (which co-acts with a grounded lever 103') via wire 103; while the remainder passes by way of a bridge 104 over to post 105' and to the corresponding contact 105. The latter is in engagement with switch segment 11 which also engages contact 37 previously referred to. Current hence flows through the bolt 37' of the latter, wire 107 and the primary coil 87, to tie-bolt 49 which may conveniently be directly connected to the primary, as at 108 (Fig. 1). A wire 109 may be connected to the tie-bolt 49 by clamping it between the nut 63 thereof and a binding nut 110, so that the bolt 49 itself constitutes a binding post; and wire 109 leads back to the grounded frame of the magneto at 111. The condenser 80 is in shunt across the primary being connected to bolt 49 by a connection 112, and to lead 101 by a wire 113.

The secondary 88 may be connected at one terminal thereof to ground via bolt 49 and wire 109, while the other secondary terminal is connected by a fine wire 114 with the stud 67, said wire preferably extending up into the small bore 68 in the stud, and being secured therein in any suitable manner.

The wire 115 leading to the usual distributor or like part may be clamped between the nuts 69 and 70 and the boss 116 of the insulating cover 59 which substantially inscloses said nuts is preferably grooved or slotted on one side thereof as at 117 for the reception of this wire.

When the system is on the battery circuit, switch handle 8 will be moved to the right, as viewed in Fig. 2, to the position marked B. At such time segments 11 and 12 will respectively engage contacts 118-105 and 106-119. The current will flow from the battery 120, in such case, via wire 121 to post 122, over wire 123 to post 119', contact 119, segment 12, contact 106, post 106', bracket 40, contacts 38-39 (the latter when the push button is not pressed inwardly, or through contacts 41-42 when said button is in its innermost position), spring 36, post 37', wire 107, primary 87, bolt 49, wire 109 to ground at 111. Thence from ground at lever 103' to insulated bracket 102, and then via wire 103, post 102', wire 101, post 100', bridge 104, post 105', segment 11, post 118',

wire 124, post 125, lead 126, back to the battery.

It will be noted that the primary condenser 80 is in circuit whether the system is on battery or magneto.

The second condenser 83 is in shunt across the push button contacts; wires 127-128 respectively leading therefrom to wires 107 and post 106'.

When the switch handle is in its median position, the battery circuit will be interrupted at 118 and also at 119; while the magneto circuit will be open at 99'.

In the secondary, should a destructive or excessive voltage be developed for any reason, the safety gap between the electrodes 74-77 will permit of a discharge directly across from the stud 67 (which is in contact with electrode 74) to the grounded tie-bolt 49 which is in electrical connection with electrode 77.

Assuming now that the secondary winding has become perforated or that for any other reason it be desired to dis-assemble portions of the structure. The nuts 110 and 63 are unscrewed, permitting of the removal of the outer cover 62. Then the removal of nut 61, frees the inner cover, exposing nuts 57 and 57', which when removed permits the withdrawal of block 55 and ring 52. Thereafter the casing 47 may be slipped off, as also the sleeves 93, permitting the ready removal of the entire induction coil. The alternate laminæ, being no longer pressed together, may be pulled apart, freeing the windings. This leaves the switch base, through bolts 48-49 and other attached parts, together with the condensers, undisturbed. The condensers obviously may then be removed; while the switch cap can be separated from the base without disturbing the parts carried upon the other side of the latter, if desired. Thus the device is as a whole exceedingly compact, substantial and simply held together. The heavy windings, core, condensers, insulating block, retaining ring and protective covers are all rigidly held together by the through bolts or tie-rods, which are directly connected to the strong metal base, so that there is no tendency to break away or become loose as the result of vibration.

The respective joints between the metal base, ring 52 and the casing are waterproof and tend to prevent any warping of the latter; while substantially no deforming stress is imposed on this casing.

The C-shaped, leaved, contact springs in the switch insure excellent contact and are capable of carrying heavy currents without injury.

No wax or the like is anywhere employed in the construction for sealing or closure purposes, while in the event of a break-down of the coil windings, which it may be here

stated are assembled in a heat-proof compound, it is unnecessary to lose even the iron core, the injured winding alone being removed.

5. Having thus described my invention, what I claim is:—

1. In ignition apparatus of the class described, a base, a tie-rod connected thereto, a condenser, pressure plates supported by 10 said tie-rod and adapted to co-act therewith for applying pressure to said condenser, and an induction coil having a magnetic core, said core also mounted on said tie-rod and supported thereby.

15. 2. In ignition apparatus of the class described, the combination of an induction coil and tie rods adapted to support said coil, a base mounted on said tie rods adjacent to said coil, a contact block mounted on 20 said base said block carrying switch contacts, a housing for said contact block, means carried by said housing and having contacts adapted to engage said switch contacts, a casing for said coil and means co-acting 25 with said tie rods for holding said casings against said base, substantially as described.

3. In ignition apparatus of the class described, a base, a conductive tie-rod connected thereto, an induction coil carried by said 30 tie-rod, an electrical connection between a secondary winding of said coil and said rod, an insulating block mounted on said tie-rod, a high-tension terminal carried by said block, and safety gap forming means electrically connected to said terminal and said tie-rod.

4. In ignition apparatus of the class described, the combination of an induction coil having high and low tension windings, and 40 connections therefor, tie rods adapted to support said coil, a base attached to one end of said tie rods, a contact block mounted on said base and carrying switch contacts, a terminal block carried by said tie rods on the opposite end from said base, said terminal block having a terminal adapted to receive the end of said high tension winding, said low tension winding being connected to 45 a contact on said contact block, a cover for 0 said contact block and means within said cover adapted to co-act with said contacts to control the connections to said low tension winding, substantially as and for the purpose described.

5. In ignition apparatus of the class described, a base, two tie-rods connected thereto, said rods being of unequal length, a tubular casing adapted to be placed under compression in the direction of its axis by 50 said tie-rods, an induction coil in said casing carried by said tie-rods, said base being disposed at one end of said casing, a closure for the other end of said casing, a terminal carried by said closure, means carried by said rods for holding said closure in

place, and a protective cover over said terminal, the longer of said tie-rods extending through said protective cover, and means co-acting with said extended tie-rod for holding said cover in place.

6. In ignition apparatus of the class described, a base, two tie-rods connected thereto, said rods being of unequal length, a tubular casing adapted to be placed under compression in the direction of its axis by said tie-rods, an induction coil in said casing, 70 said base being disposed at one end of said casing, a closure for the other end of said casing, a terminal carried by said closure, means carried by said rods for holding said closure in place, and a protective cover over said terminal, the longer of said tie-rods extending through said protective cover, and means co-acting with said extended tie-rod for holding said cover in place.

7. In a device of the class described, a base, a tie-rod connected thereto, a casing, means co-acting with said tie-rod for holding said casing and base in assembled relationship, electrical apparatus disposed in 75 said casing and carried by said tie-rod, said apparatus electrically connected to said tie-rod, one end of the latter being provided with means whereby to constitute it a binding post.

8. In combination, a casing, electrical apparatus in said casing, a closure for one end of said casing, a terminal for said apparatus carried by said closure, a base, connections between said base and closure, a cover for said closure and a portion of the terminal carried thereby, an auxiliary cover over the cover first mentioned, and means co-acting with one of said connections for holding 80 both of said covers in place.

9. In combination, a casing, electrical apparatus in said casing, a closure for one end of said casing, a terminal for said apparatus carried by said closure, a base, connections between said base and closure, a cover for 85 said closure and a portion of the terminal carried thereby, an auxiliary cover over the cover first mentioned, and means co-acting with one of said connections for holding both of said covers in place, said auxiliary 90 cover having a lateral aperture therein.

10. In combination, a casing, electrical apparatus in said casing, a closure for one end of said casing, a terminal for said apparatus carried by said closure, a base, connections between said base and closure, a cover for 95 said closure and a portion of the terminal carried thereby, and means co-acting with one of said connections for holding said cover in place.

11. In ignition apparatus of the class described the combination of a base, parallel rods projecting therefrom, an open circuit magnetic core mounted upon said rods, primary and secondary windings of an induc- 100

tion coil mounted on said core and a wrapping of sheet magnetic material surrounding said core and windings, substantially as described.

- 5 12. In ignition apparatus of the class described the combination of a base, parallel rods projecting therefrom, a magnetic core comprising T-shaped plates alternately reversed with respect to each other and strung 10 upon said rods, primary and secondary windings surrounding the stems of said plates and a wrapping of sheet magnetic material surrounding the same and the windings, substantially as described.
- 15 13. In ignition apparatus of the class described the combination of a base, parallel rods projecting therefrom, a magnetic core comprising T-shaped plates alternately reversed with respect to each other and strung 20 upon said rods, primary and secondary windings surrounding the stems of said plates and a wrapping of sheet magnetic material of the width of said core surround-

ing the same and the windings, substantially as described.

14. In ignition apparatus, the combination of an induction coil, a base, therefor, a switch mounted on said base and comprising two rotary plates secured together one of which is an insulating plate, a handle on one of said plates, said insulating plate carrying contacts and a fixed plate carrying contacts coacting with those on the insulating plate.

15. In ignition apparatus of the class described, a casing, heads at each end thereof, a tie-rod connecting the heads together and an induction coil and a condenser supported in succession on said tie-rod.

In witness whereof, I subscribe my signature, in the presence of two witnesses.

RICHARD H. CUNNINGHAM.
